CLAIM

The ornamental design for a lawn edging connector, as shown and described.

DESCRIPTION

FIG. 1 is a front perspective view of a lawn edging connector showing our new design;

FIG. 2 is a front view thereof;

FIG. 3 is a rear view thereof;

FIG. 4 a right side view thereof;

FIG. 5 is a left side view thereof;

FIG. 6 is a top view thereof; and,

FIG. 7 is a bottom view thereof.

The broken lines in the drawings illustrate portions of the lawn edging connector that form no part of the claimed design. The landscape edging connector is shown with a symbolic break in its length and height in some embodiments. The appearance of any portion of the landscape edging connector between the break lines forms no part of the claimed design.
